FIBER HOVER

Tyler D. Abercrombie, Ashburn, Ga.

Application June 9, 1938, Serial No. 212,822

1 Claim. (Cl. 119—33)

This invention relates to improvements in hovers for small chickens or the like, and more particularly to a hover which will be formed with a body portion supported upon legs, and having depending strands of fiber or hemp whereby small chickens may hover under the device to keep warm.

An object of my invention is to provide a fiber hover for small chickens, the same being supported upon suitable legs a short distance from the ground, and provided with a plurality of depending pieces of hemp rope, having their lower portions unraveled to provide a bed or mass of fiber whereby the small chickens may get in between the fibers to keep warm, and the further provision of a cap or cover for said hover provided with means for heating the hover.

Another object of my invention is to provide an improved chicken hover including a body portion having supporting legs and a plurality of transversely disposed spaced slats between which are suspended short sections of fiber or hemp rope, said sections of rope being unraveled to produce a mass effect adjacent the ground whereby the small chickens may get in between the fibers to keep warm, and the further provision of a removable cover having heating means supported therein adapted to direct heat down through the opening between the sections or pieces of the fiber or hemp rope, to assist in keeping the small chickens warm.

Another object of my invention is to provide an improved chicken hover which will be highly efficient in operation, and which will be relatively inexpensive to manufacture and produce.

Other objects will appear as the description proceeds.

In the accompanying drawing which forms a part of my application,

Figure 1 is a longitudinal sectional view through my improved fiber hover;

Figure 2 is a vertical sectional view through my improved fiber hover.

Like characters of reference are used throughout the following specification and the accompanying drawings to designate corresponding parts.

In carrying out my invention, I provide a hover for small chickens including a body portion generally denoted by the reference numeral 1, said body portion comprising the oppositely disposed side rails 2 and a plurality of transversely disposed spaced cross rails 3 secured in any desired manner to said side rails. Suitable supporting legs 4 are provided at the corners of the body

portion 1, and support the hover a slight distance from the surface of the ground, where the small chickens may readily run under the same to keep warm.

Disposed between the adjacent spaced side rails 2, I have provided a plurality of clusters of fibrous material and these clusters may consist of short lengths of hemp rope, which are attached to the edge surfaces of said rails by means of the staples 5. The sections of rope 6 extend downwardly below the body portion 1 of the hover, and have their lower extremities unraveled to provide a mass of strands arranged in close proximity to each other, to form the effect of a mat, as indicated by the reference numeral 7. As seen from the drawing, the strands of fiber forming the mat 7 will extend down to approximately one inch from the surface of the ground, where the small chickens may readily run in under the mat between the strands or fibers of the rope, thus providing an efficient form of hover. As shown in Figure 2 the secured ends of the strands 6 are spaced apart and also serve to insure proper spacing of the rails 3 while being assembled so that heated air thus is free to escape downwardly between the rails and seep between the lower portions of the suspended fibres. Consequently an even distribution of the heated air is effected.

Cooperating with the body portion 1, I have provided a substantially rectangular shaped cover 8 having depending sides 9 and ends 10. The corners of the cover 8 extend all the way down to the top of the body portion 1, but the central portions of the ends of the cover between the adjacent end corners are cut out to fit over the adjacent side rails 2 when the cover is in operative position upon the body portion 1. Thus a heating chamber is provided with the rails 3 forming the bottom thereof.

Attention is called to the fact that each row of spaced clusters of fibers is gripped by one side of the rail 3 next adjoining the rail to which the fibers are secured.

I have illustrated spring latch members 19 disposed at the opposite sides of the cover, said latches being adapted to engage and snap over the side locking means 20 formed on the opposite sides of the side rails 2, as clearly illustrated in Figure 2 of the drawing.

The opposite ends of the body portion 1 are notched out as at 21 to provide handle openings whereby the hover may be moved from place to place. It will be understood that as many of these hovers as desired may be employed, there-

by using them in bank formation, or they may be used singly, as desired.

By referring to Figures 1 and 2 it will be noted that the clusters of fibers form cross air spaces or passages 22 extending under the rails 3 so that heated air flowing downwardly through the vents between the rails will be distributed over the mass formed by the closely fitting lower or unraveled ends of the clusters and which mass substantially fills the area between the legs 4.

From the foregoing description it will be apparent that I have provided a highly efficient form of fiber hover utilizing a desired form of heating medium to assist in keeping small chickens warm, and these hovers may be used in any formation or arrangement as desired to suit the condition in the particular chicken house.

It will be understood that while I have described and illustrated one form of my improved fiber hover for small chickens, I do not intend to limit myself to this specific construction, as it is readily understood that many minor changes in detail of construction may be resorted to with-

out departure from the spirit of the invention.

Having thus described my invention what I claim as new and desire to secure by Letters Patent of the United States is:

A hover including a box-like casing defining a heating chamber, legs supporting the casing at its corners, parallel rails constituting the bottom of said chamber, a row of spaced clusters of fibrous material attached to one side of each rail and gripped by one side of the next adjoining rail, said clusters of material being suspended below the rails and all of the clusters being gradually enlarged in a downward direction to provide crossed communicating air spaces under the rails and a compact mass of fibers below said spaces substantially filling the area between the legs, said crossed spaces constituting ducts for distributing air to all portions of the mass, those portions of the clusters held between the rails being spaced to provide air vents, and a heating element in the casing above the vents.

TYLER D. ABERCROMBIE.
